Att'y.

UNITED STATES PATENT OFFICE.

OLIVER E. BUCKLEY, OF MAPLEWOOD, NEW JERSEY, ASSIGNOR TO WESTERN ELECTRIC COMPANY, INCORPORATED, OF NEW YORK, N. Y., A CORPORATION OF NEW YORK.

CONTINUOUSLY-LOADED SIGNALING CONDUCTOR.

Application filed August 16, 1921. Serial No. 492,724.

To all whom it may concern:

Be it known that I, OLIVER E. BUCKLEY, a citizen of the United States, residing at Maplewood, in the county of Essex, State of New Jersey, have invented certain new and useful Improvements in Continuously-Loaded Signaling Conductors, of which the following is a full, clear, concise, and exact description.

10 This invention relates to continuously loaded signaling conductors.

In accordance with the best approved practice, continuously loaded conductors are constructed by wrapping the bare conductor 15 with magnetic wire or tape which serves to increase the inductance of the conductor. Thus, in the case of long submarine cables, each of whose conductors is made up of a plurality of individual conducting wires, in 20 order to give flexibility to the entire cable, the wire or tape is continuously wrapped about the composite conductor.

Investigation has shown that where the construction herein referred to is used in submarine cables, the water pressure which is encountered in ordinary practice, tends to force the magnetic wire or tape into the interstices of the stranded conductor, and brings about a change in the relative positions of the loading material and the conductor. In the case of iron, the permeability of which is only slightly affected by strains of the magnitude encountered under these circumstances, no appreciable lowering of these inductances is noticed after the cable containing the iron loading has been submerged. However, with certain materials, which possess a high permeability at low magnetizing forces, applied to the conductor in the 40 manner above described, a considerable lowering of inductance is experienced when the cable is submerged even at moderate depths. The change, therefore, which takes place when high permeability material is employed indicates that to fully realize the advantages to be derived from such material precautions must be taken to prevent the material from being subjected to mechanical strains.

50 It has been found that if the composite conductor is so shaped that it presents a smooth cylindrical exterior, loading material having a high permeability at low magnetizing forces may be applied thereto either in the form of wire or tape, in such a manner that

the tendency to produce a change in the magnetic properties of said material upon submergence is greatly diminished.

The manner in which a conductor is continuously loaded in accordance with the present invention, may be more fully understood by referring to the drawings, in which Fig. 1 represents a cross section of the cable core; and Fig. 2 is a plan view of the cable with parts broken away to more readily show its 65 construction.

The composite conductor consists of a central conducting wire 3, surrounded by conducting segmental strips 4, said segmental strips being so shaped that they fit snugly 70 together to form a smooth cylindrical surface. The loading material 5, preferably in tape form, is wrapped about the composite conductor and completely surrounded by insulating material 6, such as, for example, 75 gutta percha.

The construction herein described, is further of value in that during the process of wrapping the loading tape about the conductor a cushioning effect is afforded, which 80 tends to equalize strains in the tape and thus prevent consequent reduction of permeability particularly during the subsequent processes of annealing and covering.

Other embodiments of the invention are 85 contemplated without departing from the spirit of the appended claims.

What is claimed is:

1. A loaded signaling conductor comprising a central wire, said wire being surrounded by a conducting layer composed of strips shaped to fit snugly together and form a smooth exterior surface.

2. A signaling conductor comprising a central wire, conducting strips superimposed thereupon, said strips being shaped to fit snugly together and form a cylindrical exterior surface, and magnetic material covering said segmental strips.

3. A signaling conductor comprising a central wire, a plurality of conducting strips surrounding said wire and forming a substantially cylindrical exterior surface, and a layer of magnetic material in intimate mechanical contact with the exterior surface of 105 said strips.

4. A signaling conductor comprising a plurality of conductors and a covering of magnetic material wrapped thereabout, the inner surface of said magnetic material be- 110

2
ing in mechanical contact at all points with the exterior surfaces of said conductors.

5. In combination, a conducting wire, a plurality of strips of segmental cross section surrounding said wire, and a continuous covering of magnetic material about said segmental strips.

6. In combination, a central wire, a plurality of conducting strips of segmental cross section surrounding said wire, and a covering of magnetic material over said strips.

7. The method of constructing a continuously loaded conductor which consists in surrounding a central wire with strips of segmental cross section to form a cylindrical exterior, and applying magnetic material about said segmental strips.

8. The method of constructing a continuously loaded conductor, which consists in surrounding a central wire with strips of segmental cross section to form a cylindrical exterior and applying magnetic material having high permeability at low magnetizing forces about said segmental strips. 20

9. A signaling conductor comprising a central wire, conducting strips of segmental cross section superimposed thereupon, and a magnetic material having high permeability at low magnetizing forces covering said segmental strips. 25

30 In witness whereof, I hereunto subscribe my name this 10th day of August, A. D. 1921.

OLIVER E. BUCKLEY.
